WEEDING TOOL

Kaneo Futami, 319 N. Vancouver Ave.,
Los Angeles, Calif. 90022

Filed July 7, 1969, Ser. No. 18,084

Term of patent 7 years

Int. Cl. D8—01

U.S. Cl. D8—4

FIG. 1 is a right front perspective view of a weeding tool, showing my new design;

FIG. 2 is a rear elevational view;

FIG. 3 is a left side elevation view;

FIG. 4 is a top plan view; and

FIG. 5 is a bottom view.

I claim:

The ornamental design for a weeding tool, substantially as shown and described.
